UNITED STATES PATENT OFFICE

THOMAS S. MERRYLEES, OF YEADON, PENNSYLVANIA

LIQUID COOLER

Application filed August 10, 1928, Serial No. 298,675. Renewed September 7, 1929.

This invention relates to coolers of the fountain type wherein a receptacle for cracked pack ice encloses a jar which is surmounted by an inverted receptacle containing the supply of water or other liquid which is to be cooled.

The purpose of my invention is to enable conversion of coolers of the kind referred to so that solidified carbon dioxide or the like can be conveniently and economically used as a refrigerant in them in lieu of ordinary cracked ice with maintenance of the water at a palatable drinking temperature. As hereinafter fully explained, I attain this desideratum by packing thermo-insulation into the space at the interiors of the coolers initially intended for the pack ice, with incidental formation of flanking pockets or chambers just large enough to accommodate standardized unit blocks of the solidified carbon-dioxide in contact with the water jar.

My invention is also concerned with provisions whereby the blocks of the solidified carbon dioxide, notwithstanding diminution in size due to sublimation, are maintained at all times in efficient surface pressure contact with the water jar.

With reference to the drawings, Fig. I shows a perspective view of a liquid cooler of the ordinary fountain type converted for use of solid carbon dioxide in accordance with my invention.

Fig. II is a plan view of the converted cooler with the lid removed or as indicated by the arrows II—II appearing on Fig. IV.

Fig. III is a plan section taken as indicated by the arrows III—III in Fig. IV.

Fig. IV is an axial section taken as indicated by the arrows IV—IV in Figs. II and III.

Fig. V is a vertical section in a plane at right angles to that of Fig. IV or taken as indicated by the arrows V—V in Fig. II.

Figs. VI and VII are perspective views showing the component parts of the divided lid of the cooler.

Fig. VIII is a perspective view of an insert forming a part of the conversion means.

Fig. IX is a similar view of one of the covers protecting the openings into the pock-

ets or chambers which accommodate the blocks of the solidified carbon dioxide.

Figs. X and XI show perspective views of parts constituting means for maintaining the carbon dioxide blocks in contact with the jar containing the liquid being cooled.

Fig. XII shows a perspective view of an alternate form of wedge.

The cooler herein delineated embodies an outer cylindrical casing 15 that constitutes a receptacle—originally intended for cracked pack ice—around a jar 16 occupying a slightly off center position toward the front of the cooler, see Figs. I, II, III and V. As shown, the jar 16 is surmounted by a container in the form of a bottle 17 holding the supply of the water or other liquid which is to be cooled, the bottle being inverted and its mouth fluid sealed in the jar. As a consequence, the liquid in the jar 16 is automatically replenished in proportion to quantities drawn off through a pipe 18, the latter extending forward from the bottom of said jar and through the side wall of the receptacle 15 to the exterior where it is equipped with a drain faucet 19,—all after usual and well known practise.

To convert a cooler of the kind briefly described for the purposes of my invention, I employ an insert 20 which is shown in perspective in Fig. VIII. In the present instance, this insert 20 is fashioned from sheet metal with a rounded central portion 20^a to fit about the jar 16 with slight circumferential clearance, and square flanking offsets 20^b with sloping end walls 20^c at opposite sides of said central portion,—the whole being lined with a layer of cork or other suitable thermo-insulation in sheet form as at 20^d. Upon placement of the insert 20 over the jar 16 with its offsets 20^b symmetrically positioned relative to a vertical plane fore and aft centrally through the cooler, I pack a thermo-insulate composition 21 (which may be of granular cork with a suitable congealing binder) into the remaining space within the receptacle 15 to a level somewhat below its brim, with incidental formation however of openings 22 having walls in continuation with those of the offsets 20^b for convenience of access to

the latter from the top of the cooler. It is to be particularly noted in this connection, that the insert 20 serves after the manner of a retaining wall for the insulate body 21, its offsets defining pockets or chambers 23 each just large enough to accommodate, for example, a standardized half pound block B of solidified carbon dioxide (measuring approximately four by two by one inches) in surface contact with the jar 16.

To insure continuous pressure contact at all times notwithstanding shrinking through evaporation, I provide wedge means to urge the blocks B toward the jar. As shown, this wedge means may comprise a backing plate 25 (Fig. X) of metal having a facing 25^a of insulation for contact with the block B, and a gravity roller 26 (Fig. XI) which is dropped into the interval within the pocket or chamber 23 between the backing plate 25 and the sloping end wall 20^c of said chamber. Thus, as the block B gradually decreases in thickness, the roller 26 automatically descends progressively, thereby, through cooperation with the sloping end wall, causing the backing plate to move inward to maintain said block in contact with the jar as aforesaid.

In place of the backing plate 25 and roller 26, I may use a wedge of the form illustrated in Fig. XII. The wedge 37 there shown operates in the same manner to maintain the refrigerant block B in contact with the jar 16 and has a finger-grip 37^a to assist its removal from the chamber 23.

For protection against injury, I cover the exposed surfaces of the insulate packing 21 with canvas or other suitable material as conventionally indicated at 27 in Figs. IV and V. The openings 22 into the pockets or chambers 23 are protected by removable plug-like covers 28 of insulation with perimetric flanges 28^a to seat in recesses 29 about the tops of said openings, and with finger-grips 28^b, one such cover being illustrated in inverted perspective in Fig. IX. For a closure over the top of the receptacle 15 I provide a diametrically divided lid with counterpart components 30, 31 separately shown in perspective in Figs. VI, VII. The lid components 30, 31, it will be observed, have registering semi-circular cut-outs 30^a, 31^a in their straight edges to clear the protruding top of the jar 16, and thickened central areas 30^b, 31^b that reach down to the depressed top surface of the insulate filling 21 flush with the covers 28.

Radiation through the bottom of the receptacle is effectively checked by filling the clearance space beneath it with insulate component 35 which may be of the same character as that employed within the receptacle, and then permanently securing a retaining disk 36 of wood or fiber thereunder.

In operation of the cooler, the refrigerating effect of the solidified carbon dioxide,

whereof the temperature is in the neighborhood of -100° F., is effectively modified incident to transmission through the comparatively thick shell of the ceramic jar 16, as well as through diffusion of the evaporated gas between the chambers 23 about the jar as a consequence of the circumferential clearance afforded within the rounded portion 20^a of the insert 20. Freezing is positively prevented by virtue of direct communication of the jar 16 with the large bulk of the liquid and air in the bottle 17 subject to outside atmospheric influence.

From the foregoing it will be seen that through my invention I am able to convert, at small cost, standard liquid coolers for use of solidified carbon dioxide blocks with provision of a modified structure, wherein, by virtue of enclosure in heavily insulated chambers, the blocks are protected against rapid sublimation while in effective contact with the jar containing the liquid being cooled. It is, furthermore, noteworthy that the conversion is accomplished without in any way altering the original construction of the coolers. With an ordinary cooler converted after the manner herein disclosed, it is demonstrable that, with all conditions equal, a pound of solidified carbon dioxide can be made to last as long as twenty to twenty-five pounds of ordinary cracked ice, the comparative quantities of the two refrigerants costing about the same. Finally, the expense of conversion is more than offset by the advantages gained through use of the solidified carbon dioxide which disappears completely in contradistinction with the sloppiness attendant upon evaporation of ordinary ice and the frequent attention necessary in removing the residue.

Having thus described my invention, I claim:

1. Conversion means of the character described for liquid coolers of the fountain type—wherein an ice receptacle surrounds a jar receiving the liquid to be cooled from an inverted supply container—comprising a body of thermo-insulation to fill the space around the jar within the receptacle aforesaid but with provision of flanking chambers each just large enough to accommodate a standardized unit block of solidified carbon dioxide in contact with the jar.

2. Conversion means of the character described for liquid coolers of the fountain type—wherein an ice receptacle surrounds a jar receiving the liquid to be cooled from an inverted supply container—comprising a body of thermo-insulation to fill the space around the jar within the receptacle aforesaid but with provision of flanking chambers each just large enough to accommodate a standardized unit block of solidified carbon dioxide in contact with the jar, said chambers being accessible from the top of the re-

ceptable through openings protected by individually removable covers.

3. Conversion means of the character described for liquid coolers of the fountain type—wherein an ice receptacle surrounds a jar receiving the liquid to be cooled from an inverted supply container—comprising a body of thermo-insulation filling the space around the jar within the receptacle but with provision of flanking chambers each large enough to accommodate a standardized unit block of solid carbon dioxide in contact with the jar, said chambers being accessible from above through openings protected by individually removable covers, and a divided lid fitting the top of the receptacle over the openings into the chambers.

4. Conversion means of the character described for liquid coolers of the fountain type—wherein an ice receptacle surrounds a jar receiving the liquid being cooled from an inverted supply container—comprising an insert forming a retaining wall about the jar with provision of flanking chambers each accommodating a standardized unit block of solidified carbon dioxide in contact with the jar, and a body of thermo-insulation compound filling all the remaining space between the insert and the wall of the receptacle aforesaid.

5. Conversion means of the character described for liquid coolers of the fountain type—wherein an ice receptacle surrounds a jar receiving the liquid to be cooled from an inverted supply container—comprising an insert of metal lined with a layer of thermo-insulation and forming a retainer wall about the jar with provision of flanking chambers each accommodating a standardized unit block of solid carbon dioxide in contact with the jar, and a body of thermo-insulation compound filling all remaining space between the insert and the wall of the receptacle aforesaid.

6. Conversion means of the character described for liquid coolers of the fountain type—wherein an ice receptacle surrounds a jar receiving the liquid to be cooled from an inverted supply container—comprising a body of thermo-insulation to fill the space around the jar within the receptacle aforesaid but with provision of flanking chambers, each accommodating a standardized unit block of solidified carbon dioxide, and means within said chambers to maintain the blocks of the refrigerant in contact with the jar.

7. Conversion means of the character described for liquid coolers of the fountain type—wherein an ice receptacle surrounds a jar receiving the liquid to be cooled from an inverted supply container—comprising a body of thermo-insulation to fill the space around the jar within the receptacle but with provision of flanking chambers having

walls sloping downwardly and inwardly toward the jar, each of said chambers being adapted to accommodate a standardized unit block of solidified carbon dioxide in contact with the jar.

8. Conversion means of the character described for liquid coolers of the fountain type—wherein an ice receptacle surrounds a jar receiving the liquid to be cooled from an inverted supply container—comprising a body of thermo-insulation to fill the space around the jar within the receptacle but with provision of flanking chambers with walls sloping downwardly toward the jar, each of said chambers being adapted to accommodate a standardized unit block of solidified carbon dioxide, and means in the chambers to maintain the carbon dioxide blocks in contact with the jar, including in each instance a backing plate for the block, and a gravity roller operating as a wedge between the sloping wall of the chamber and the backing plate.

9. Means adapted to convert a liquid cooler, of the type comprising an ice receptacle surrounding a jar for receiving the liquid from an inverted supply container, for use with solid carbon dioxide as a refrigerant, said means comprising a body of thermo-insulation adapted to fill the space around the jar within the receptacle and having chambers adjacent the jar accommodating a standardized unit block of said refrigerant, and means for maintaining the refrigerant in contact with the jar as it evaporates.

10. Means adapted to convert a liquid cooler, of the type comprising an ice receptacle surrounding a jar for receiving the liquid from an inverted supply container, for use with solid carbon dioxide as a refrigerant, said means comprising a body of thermo-insulation adapted to fill the space around the jar within the receptacle and having chambers adjacent the jar accommodating a standardized unit block of said refrigerant, said chambers having walls sloping downwardly toward the jar, and wedge means operating between the sloping walls of the said chambers and the refrigerant blocks to maintain them in contact with the jar.

11. The method of converting liquid coolers of the fountain type—wherein an ice receptacle surrounds a jar receiving the liquid to be cooled from an inverted supply container—by filling the space around the jar within the receptacle with a thermo-insulating compound and incidentally forming flanking chambers each just large enough to accommodate a standardized unit block of solidified carbon dioxide in contact with the jar.

12. Conversion means of the character described for liquid coolers, wherein a cooling medium receptacle surrounds a container for the liquid to be cooled, comprising a body

of thermo-insulation filling the space about the container within the receptacle aforesaid, and pockets in said thermo-insulation for reception of solidified frigorific-medium blocks maintained in surface contact with the container by gravity influence.

In witness whereof, I have hereunto signed my name at Philadelphia, Pennsylvania, this 8th day of August, 1928.
